(57) **CLAIM**

The ornamental design for an aircraft cabin, as shown and described.

DESCRIPTION

FIG. 1 is a perspective view of an aircraft cabin showing our new design; and,

FIG. 2 is a side elevational view taken from the longitudinal center of FIG. 1.

The dot-dash lines in FIGS. 1 and 2 represent the boundaries of the claim and form no part thereof.

1 Claim, 2 Drawing Sheets Fig. 1
